ELECTRICAL CONTROLLER CASING

Raymond L. Erickson, Brookfield, Wis., assignor to Cutler-Hammer, Inc., Milwaukee, Wis., a corporation of Delaware

Filed Oct. 23, 1967, Ser. No. 9,127

Term of patent 14 years

(Cl. D26—13)

Fig. 1

Fig. 2

Fig. 3

Fig. 4

Fig. 5

Fig. 6

FIGURE 1 is a perspective view of an electrical controller casing, showing my new design;

FIG. 2 is a front elevational view thereof;

FIG. 3 is a right-end elevational view thereof having a portion broken away to fragmentarily disclose the transverse cross-section thereof;

FIG. 4 is a top plan view thereof;

FIG. 5 is a front elevational view of the electrical controller casing shown in FIG. 1 but showing a modified embodiment thereof; and

FIG. 6 is a top plan view thereof.

The dominant features of my new design are shown in full lines.

I claim:

The ornamental design for an electrical controller casing, substantially as shown and described.
